UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 13,991, dated June 19, 1883

Application filed May 4, 1883. Term of patent 3½ years

To all whom it may concern:

Be it known that I, PAUL PIGNOT, of Yonkers, Westchester county, New York, have invented a new and original Design for Carpets, of which the following is a specification.

5 The accompanying photograph illustrates my new design for carpets.

This invention relates to a new design for carpets, oil-cloths, and analogous fabrics; and 10 it consists of the new ornamentation of parts, hereinafter more fully pointed out.

Around a scroll-like figure, A, which winds through the carpet, are clustered series of flowers B, which appear to embrace the scroll,

15 while other flowers, C, overhang the scroll, leaving a space, D, partly free, as though it were an opening through which the setting sun could be observed through a bower built up of flowers.

I claim—

20 The design for carpets, consisting of the scroll A, flowers B C, and field or space D, substantially as shown.

PAUL PIGNOT.
